UNITED STATES PATENT OFFICE.

CHARLES ZIMMERLING, OF PHILADELPHIA, PENNSYLVANIA, ASSIGNOR TO
E. K. TRYON, JR., OF SAME PLACE.

SOAP.

SPECIFICATION forming part of Letters Patent No. 286,568, dated October 9, 1883.

Application filed September 6, 1883. (No model.)

To all whom it may concern:

Be it known that I, CHARLES ZIMMERLING, a citizen of the United States, residing in the city and county of Philadelphia, State of Pennsylvania, have invented a new and useful Improvement in Soap, which improvement is fully set forth in the following specification and accompanying drawings, in which—

Figures 1 and 2 are top or plan views of 10 cakes of soap embodying my invention. Fig. 3 is a section in line *x x*, Fig. 1. Fig. 4 is a side elevation of a modification. Fig. 5 is a top or plan view of a modification. Fig. 6 is a side elevation thereof. Fig. 7 is a side 15 elevation of a modification. Fig. 8 is a section thereof in line *y y*, Fig. 7.

Similar letters of reference indicate corresponding parts in the several figures.

My invention consists of a cake or piece of 20 soap having on the face thereof a pocket to receive a box or package of merchandise, and an opening leading to said pocket, whereby, by the insertion of the finger or a suitable implement in said opening, the box or package 25 may be conveniently removed.

It also consists in applying to the box or package a coating of preservative nature.

Referring to the drawings, A represents a cake or piece of soap, and B represents a 30 pocket formed in said cake or piece to receive a box or package, C, containing or consisting of any desirable merchandise—such as blacking, bluing, stove-polish, &c.—thus conveniently packing said merchandise with the soap.

In the soap there is formed an opening, D, 35 which extends at or about a right angle to the pocket B, whereby, by the insertion of the finger or any suitable implement, the box or package C may be readily pushed from the pocket, and thus removed.

In Figs. 3 and 4 the openings D extend at a right angle, respectively, to the bottom and sides of the box or package. The box or package is dipped in paraffine or wrapped in paraffine-paper, the object whereof is to protect 45 said box or package from injurious action of

the soap, and vice versa, and the combined articles may be shipped to distant places and remain in stock without deterioration.

It will be noticed that in Fig. 3 the opening D extends only to a partial extent through the cake. This leaves a wall, a, between the base of the pocket or recess B and inner end of the opening. Should air reach the pocket through the opening D, it will dry the sides 55 thereof, thus causing the soap to contract and tightly compress the box or package, occasioning much difficulty in removing the same. The wall a prevents such action, but may, however, be punched through by the finger or 60 an implement when required to remove the box or package, as is evident.

It is evident that I may use any other preservative coating in lieu of paraffine or paraffine-paper.

Having thus described my invention, what I claim as new, and desire to secure by Letters Patent, is—

1. As a new article of manufacture, a combined cake or piece of soap and article of merchandise, the same consisting of the cake or piece having a pocket or recess in which a box or package of such merchandise is fitted and retained, substantially as and for the purpose set forth.

2. A cake of soap provided with a pocket or recess and an opening leading thereto, substantially as and for the purpose set forth.

3. A cake of soap provided with a pocket or recess and an opening extending partly 80 through the same, leaving a wall between said recess and opening, substantially as and for the purpose set forth.

4. A cake of soap provided with a pocket or recess, and an article of merchandise having a preservative coating fitted in said recess, substantially as and for the purpose set forth.

CHARLES ZIMMERLING.
